A. A. HUNZIKER.

EASEL.

APPLICATION FILED APR. 12, 1917.

1,247,275.

Patented Nov. 20, 1917.

UNITED STATES PATENT OFFICE.

ADOLPH A. HUNZIKER, OF MAPLEWOOD, MISSOURI, ASSIGNOR TO WOODWARD & TIERNAN PRINTING CO., OF ST. LOUIS, MISSOURI, A CORPORATION OF MISSOURI.

EASEL.

1,247,275.

Specification of Letters Patent. Patented Nov. 20, 1917.

Application filed April 12, 1917. Serial No. 161,448.

To all whom it may concern:

Be it known that I, ADOLPH A. HUNZIKER, a citizen of the United States of America, a resident of Maplewood, in the county of St. Louis, State of Missouri, have invented certain new and useful Improvements in Easels, of which the following is a full, clear, and exact description, reference being had to the accompanying drawings, forming a part of this specification.

My invention relates to an easel for supporting show cards, advertising signs, and the like, such as are ordinarily displayed in stores, the easel comprising essentially a member by which it may be attached to the show card or sign, a supporting wing hinged to said attaching member, and a retaining member hinged to the attaching member and interlocked with the supporting wing. The invention has for its object a construction that will provide an interlocking connection between the retaining member and the supporting wing which is simple and so positive as to avoid liability of the separation of the parts while the easel is in service, but which may be readily disengaged without detracting from the ability of the parts to perform their function when the interlocking connection is reestablished.

Figure I is a perspective view of my easel. Fig. II is a side elevation.

Fig. III is a horizontal cross section taken on line III—III, Fig. II.

Fig. IV is a front elevation of the easel in unfolded condition.

Fig. V is a perspective view of a modified form of the easel.

My easel is preferably formed from a single sheet A of suitable material, for example, cardboard, the construction illustrated in Figs. I to IV, inclusive, including a front section 1, a pair of side wings 2 hinged to the side edges of the front section so that said wings may be folded into parallel relationship to serve as supports for the front section 1 and the display card, or other article to which the front section is attached. The hinging of the side wings 2 to the front section 1 is preferably provided for by creasing or scoring the sheet of material from which the easel is formed along lines at which the hinges are to exist.

3 designates a retaining wing which is produced by cutting it from the sheet of material from which the easel is produced,

the cutting being so accomplished as to leave an end of the retaining wing connected to the front section 1, and this end is hinged to the front section, as seen at 4, so that the retaining wing may be bent rearwardly to occupy a position between the pair of supporting wings 2. The retaining wing 3 is provided with side tongues 5 cut from the material in the supporting wings 2 before the sheet A is folded on the hinge lines a, Fig. IV, in forming the blank of the easel. The tongues are preferably located intermediate of the ends of the retaining wing, thereby providing an end extension 6 beyond the tongues with an object in view which will hereinafter appear.

In each of the side wings 2 is a slot 7 adapted to receive one of the tongues 5 of the retaining wing 3. These slots extend transversely, or approximately horizontally, in the side wings and they are of widths corresponding approximately to the thicknesses of the tongues 5 and at least partially curved, as shown, necessitating bowing of the tongues 5 previous to passage through said narrow slots to secure the side wings to the retaining wing. The said tongues are easily bowed for passage through the slots, but immediately after their passage through the slots straighten out so that they bear against the outer faces of the side wings, and partially out of alignment with the narrow slots, and therefore confine the side wings between the tongues 5 and the side edges of the retaining wing 3. An extension 6 of the retaining wing projecting beyond the tongues 5 provides abutments at the rear end of the retaining wing against which the inside faces of the side wings bear, in addition to their bearing against the edges of the retaining wing in front of the tongues 5, and the interlocking connection between the retaining wing and the side wings is therefore much more substantial than it would be in the absence of the extension 6.

In Fig. V I have shown a modified form of my easel, the construction here shown comprising a front section 1^a and a single side wing 2^a hinged thereto and having a curved slot 7^a therein. This modified construction also includes a retaining wing 3^a cut from the front section and provided with a tongue 5^a which extends through the curved slot 7^a to hold the side wing at sub-

stantially a right angle to the front section. The modified construction differs essentially from the previously described construction, mainly in that it includes only a single side wing instead of a pair of side wings.

I claim:

1. An easel of the character described comprising a front section, a side wing hinged to said front section, one of said members having a narrow curved slot therein, and the other member being provided with a retaining wing having a tongue adapted to be inserted through said curved slot to hold said members at an angle relative to each other, said slot being of a width corresponding, approximately, to the thickness of said tongue.
2. An easel of the character described comprising a front section, a side wing hinged to said front section, said side wing being provided with a narrow curved slot, and a retaining wing hinged to said front section having a tongue insertible through said curved slot for interlocking engagement with said side wing, said slot being of a width corresponding, approximately, to the thickness of said tongue.
3. An easel of the character described comprising a front section, a side wing hinged to said front section, said side wing having a narrow curved slot therein, and a retaining wing hinged to said front section, said retaining wing having a tongue at one of its sides intermediate of its ends adapted to be inserted through said curved slot to lock said side wing to said retaining wing, said slot being of a width correspond-

ing, approximately, to the thickness of said tongue.

4. An easel of the character described comprising a front section, a pair of side wings hinged to the side edges of said front section, each of said side wings having a narrow curved slot therein, and a retaining wing hinged to said front section, said retaining wing being provided with tongues extending from its side edges adapted to be inserted through said curved slots to lock said side wings to said retaining wing, said slots being of widths corresponding, approximately, to the thicknesses of said tongues.

5. An easel of the character described comprising a front section, a pair of side wings hinged to the side edges of said front section, each of said side wings having a narrow curved slot therein, and a retaining wing hinged to said front section, said retaining wing being provided with tongues of thicknesses corresponding, approximately, to the widths of said narrow slots, said tongues extending from the side edges of said wings being adapted to be inserted through said curved narrow slots to lock said side wings to said retaining wing, the said tongues being located intermediate of the front and rear ends of said retaining wing, thereby providing for the abutment of said side wings against the side edges of said retaining wing in front of, and back of, said tongues.

In testimony that I claim the foregoing I hereunto affix my signature.

ADOLPH A. HUNZIKER.
